UNITED STATES PATENT OFFICE.

OLUF TYBERG, OF BROOKLYN, NEW YORK, ASSIGNOR TO INTERNATIONAL CIGAR MACHINERY COMPANY, OF JERSEY CITY, NEW JERSEY, A CORPORATION OF NEW JERSEY.

CIGAR-FILLER AND METHOD OF PREPARING SAME.

No. 827,126.

Specification of Letters Patent.

Patented July 31, 1906.

Application filed August 27, 1903. Serial No. 170,905.

To all whom it may concern:

Be it known that I, OLUF TYBERG, a citizen of the United States, residing at Brooklyn, county of Kings, and State of New York, have invented certain new and useful Improvements in Cigar-Fillers and Method of Preparing Same, fully described and represented in the following specification and the accompanying drawings, forming a part of the same.

This invention relates to improvements in cigar-filters and to a method of preparing the same, and particularly to cigar-filters designed for use in the manufacture of cigars by machinery.

In the manufacture of such cigars by machinery the filler material is severed into suitable lengths or sections to form fillers, which are fed by suitable conveying mechanism, either with their tuck ends or head ends in the lead, to a bunching mechanism which rolls the filler into a bunch, the bunch thus formed being thereafter wrapped and the cigar thus completed.

As usually manufactured the heads and tuck ends of cigars vary in taper and also in thickness, the head end of the cigar being usually more tapered and of less diameter than the tuck end. This difference in taper and in thickness between the head and tuck end of a cigar is usually provided for by cutting away a part of the tobacco at opposite ends of the length or section of filler, the portion thus cut away being greater at that end of the filler which is to form the head of the cigar than that which is to form the tuck end of the cigar.

In the manufacture of cigars by machinery it has been heretofore proposed to prepare the fillers for the cigars in the following manner: The pieces of tobacco which are to form the filler were assembled in a pile or mass of suitable thickness and of such length as to provide for several filler sections or lengths, which were severed from the mass or pile of filler material by two sets of cutting devices, each of which made transverse serrated or zigzag cuts in the pile or mass, the two cuts being made at such a distance apart as to provide between them a length or section of filler suitable for the formation of a cigar. As the filler sections or lengths were thus severed from the pile or mass

they were conveyed by suitable feeding mechanism to rolling devices for forming each section of filler into a bunch, which was afterward wrapped and rerolled into a completed cigar.

In the method here referred to one of the cutting devices employed made a serrated cut in the pile or mass of filler material which left long slender interlocking projections on the two edges of the cut or adjacent ends of two sections or lengths, while the other cutting device made a cut which left shorter interlocking projections on the two edges of that cut. With such a method of cutting as this it will be observed that as a result of the first cut referred to the rear end of the leading section or length of filler and the leading end of the following section each form the head of a cigar, while the rear end of the latter section or length and the forward end of the next section or length formed by the second cutting device referred to will each form the tuck end of a cigar.

In the manufacture of cigars by machinery the filler sections or lengths must be fed to the bunching mechanism in a certain order—that is to say, they must all be fed head first or they must all be fed tuck-end first. With such a method of cutting, however, as that just described it will be observed that in order to produce this feed of the fillers—that is, all head first or all tuck-end first—it is necessary to reverse every second filler section or length severed from the pile or mass. This is objectionable, as it takes time, and it is further objectionable because the handling of each second section or length of filler may and probably will result in disturbing the pieces of tobacco of which it is formed.

The object of the present invention is to provide a filler and a method of preparing the same which will obviate this difficulty.

As a full understanding of the present invention can best be had by a detailed description of the same, such description will now be given, reference being had to the accompanying drawings, in which—

Figure 1 is a plan view of a pile or mass of filler material severed into sections or lengths in such way that the two edges of each cut—that is, the rear end of the leading section or length of filler and the leading end of the

next section or length of filler—are of different formation, so that one may form the tuck end and the other the head end of a cigar. Fig. 2 is a similar view illustrating a modification of the filler and method of cutting the same illustrated in Fig. 1. Fig. 3 is a plan view of a filler-section produced by the method of cutting illustrated in Fig. 1. Fig. 4 is a similar view illustrating the filler produced by the method of cutting illustrated in Fig. 2, and Fig. 5 is a similar view of a cigar made from the filler illustrated in Fig. 3 or Fig. 4.

Referring to Figs. 1 and 3 of said drawings, 15 A represents a pile or mass of filler, and B a section or length of filler severed therefrom. The section or length B of filler illustrated in Fig. 3 is severed from the pile or mass A of filler material by means of a suitable cutting 20 tool or tools, which cut through the mass or pile on the lines *a a* and the lines *b b*. These cuts may be formed simultaneously or successively and by means of any suitable cutting devices. As a result of this method of 25 cutting it will be observed that at the rear end of the leading section or length of filler there are formed short projecting portions *c* of tobacco, while at the leading end of the following section there are formed longer projections *d* of tobacco, the end of the filler-section 30 containing the short section *c* being designed to form the tuck end of the cigar, while that end which contains the projections *d* of tobacco is designed to form the head of the cigar. In the formation of these 35 cuts it will be observed also that small portions *e* of tobacco are cut out of and removed from the mass or pile A.

Referring now to Figs. 2 and 4, it will be 40 observed that the pile or mass of filler material is severed by means of a suitable cutting tool or tools on the lines *a' b'*, a very small portion *e'* of tobacco being cut out of the pile or mass between each of the cuts *a' b'*. As a 45 result of this method of cutting there is produced a filler section or length of the form illustrated in Fig. 4, the projections *d'* in the latter being somewhat shorter than the projections *d* in the filler-section illustrated in 50 Fig. 3, while the projections *c'* are a little thicker or wider than the projections *c* in the

filler illustrated in Fig. 3. In either case—that is to say, according to the method of cutting illustrated in Fig. 1 or that illustrated in Fig. 2—there is produced in the pile or 55 mass A sections or lengths B of filler with the adjacent ends or edges of each two filler sections or lengths having dissimilar shapes or cuts, so that as each section or length of filler is severed from the mass or pile it may be fed 60 forward to the bunching-machine (head first or tuck-end first, according to the arrangement of the bunching mechanism) without the reversal of any of the sections or lengths, which is necessary in prior methods of cutting and preparing fillers for the manufacture of cigars by machines as before pointed out.

What I claim is—

1. The method of preparing cigar-filler 70 which consists in first arranging the filler material in a suitable pile or mass and then severing the mass transversely into sections of suitable lengths, the line of cut being such as to leave projecting portions at the rear end of 75 the leading section and the forward end of the next succeeding section, the projecting portions on one side of the cut being different in shape and containing different amounts of tobacco from those on the other side of the 80 cut, whereby the cut end of the section on one side of the cut is adapted to form the tuck end of a cigar and the cut end of the section on the other side of the cut is adapted to form the head end of another cigar. 85

2. A pile or mass of filler material having transverse cuts therein, the rear end of each section or length of filler and the forward end of the following section or length being different in length and shape and containing different quantities of tobacco, whereby one of 90 said ends will form the tuck end of a cigar and the other the head of another cigar, substantially as described.

In testimony whereof I have hereunto set 95 my hand in the presence of two subscribing witnesses.

OLUF TYBERG.
